UNITED STATES PATENT OFFICE.

ROBERT W. SCOTT AND LOUIS N. D. WILLIAMS, OF PHILADELPHIA,
PENNSYLVANIA.

STOCKING.

SPECIFICATION forming part of Letters Patent No. 430,695, dated June 24, 1890.

Application filed June 20, 1889. Serial No. 314,988. (No model.)

To all whom it may concern:

Be it known that we, ROBERT W. SCOTT and LOUIS N. D. WILLIAMS, both citizens of the United States, and residents of Philadelphia, Pennsylvania, have invented certain Improvements in Stockings, of which the following is a specification.

The object of our invention is to so knit a stocking that it will be full-fashioned (that is to say, properly shaped) throughout, but can be more cheaply and readily produced than an ordinary full-fashioned stocking; and this object we attain in the manner herein-after set forth, reference being had to the accompanying drawings, in which—

Figures 1, 2, and 3 are diagrams showing the successive stages in the production of a knitted stocking in accordance with our invention, and Figs. 4 and 5 are diagrams serving to illustrate the method of producing the improved stocking.

In Figs. 1, 2, and 3 the wales are represented by plain lines, the views being on too small a scale to warrant the representation of the stitches of which the wales are composed.

In carrying out our invention we first form the leg portion of the stocking, with properly-shaped heel thereon, and then knit to this leg portion a shaped tube for the body of the foot, in the manner which we will now proceed to describe.

In making the leg we use, by preference, a machine having opposite rows of needles A B, Fig. 4, and we preferably start the leg at the bottom of the heel by forming an initial course in rib stitch upon the needles of both rows throughout the length desired for the bottom of the heel, the thread being applied first to a needle of the row A and then to a needle of the opposite row B, and so on. The thread is then traversed or carried during the knitting from the needle at the point *x* of the row A to the needle at the point *y* of the same, thence across to the needle at the point *y* of the row B, thence to the needle at the point *x* of the same, thence back to the needle at the point *y*, thence across to the needle at the point *y* of the row A, thence to the needle at

the point *x* of the same, and so on until the desired length of fabric for the heel is produced, additional needles being thrown into action successively at the points *y* of both rows at the beginning of the operation, so as to gradually widen the web—say to about the point *w*—after which the knitting is continued upon the needles then in action until the desired length of heel has been produced. The effect of this operation is to produce a bag or pocket D with seamless bottom, selvaged front edges *a a*, and tapered or rounded lower corner *b*, as shown in Fig. 1. The needles in each row from *x* to *v* are now thrown into action, and continuous courses of stitches are produced, first upon the needles of one row and then upon the needles of the other row, these webs being connected at the ends and being of a width equal to the distance from *v* to *w* in Fig. 3—that is to say, of a width necessary for the ankle portion F of the stocking to be produced. A rib course is, by preference, formed upon the needles of both rows in commencing to knit the ankle portion of the stocking, so as to insure the proper formation of stitches in the first ankle-course, which is that around the edge *d* in Fig. 1, and is represented by the dotted line *l* in Fig. 2, the rib-course being removed prior to applying the ankle stitches to another machine for forming the foot, as hereinafter set forth.

After the desired length of ankle portion has been knitted the needles of each row beyond the needles *w* are successively thrown into action, so as to gradually widen the knitted tube and form the calf portion G of the stocking, this widening being continued until the needles, say, up to the point *u* are in action and the tube is of the proper size for the calf portion of the leg, the tube being knitted of this size up to the top of the leg. The leg being removed from the machine on which it was produced, the loops around the edges *d d* of the front half of the ankle portion of the tube are applied to the needles of one-half of a separate machine—for instance, to the needles on the row A of the machine,

(shown in Fig. 5,) and the production of the tube for the body of the foot of the stocking is proceeded with upon this second machine, the upper half or instep portion of the tube being thus united by a seamless union to the lower edge of the front half of the ankle portion of the leg tube, while the other or under half of the tube is free, as shown in Fig. 2. Immediately upon commencing to form the foot-tube, the latter is narrowed by dropping a number of wales, preferably at each end of the machine, say, up to the line *m m*, Fig. 5, thus forming narrowings on each side of the foot, as at *m'*, Fig. 2, so that the foot portion 5 of the stocking is widest at the commencement or instep portion of the same, and is gradually narrowed until it is of the proper diameter for the body of the foot. After the foot has been properly narrowed it is knitted 10 to the desired length for the body of the foot, and is then narrowed by dropping out wales at each end of the machine, say, up to the line *p*, as shown in Fig. 5, these narrowing operations being, by preference, performed 15 in the manner set forth in our application for patent filed May 16, 1889, Serial No. 310,965.

The last narrowing operations contract the diameter of the tube to the proper shape for the toe, and on casting off the tube from the 20 machine looped edges *f f* are presented, which are secured together in order to close the toe, as shown at *s*, Fig. 3, the stocking being completed by securing the looped edges *g g* at the inner end of the foot-tube to the selvage 25 edges *a a* at the front of the heel-pocket, as shown at *t* in Fig. 3. By this means a full-fashioned or perfectly-shaped stocking, without any objectionable seams, is produced at a more rapid rate and at less expense than in 30 making a full-fashioned stocking in the ordinary way.

Although in carrying out our invention it is advisable to form the narrowings in the 45 foot portion of the tube at the inner or instep end of the same, the essential features of our invention may be embodied in a stocking in which these narrowings are omitted, and it will be evident that in making the leg of the 50 stocking an operation the reverse of that formerly described may be adopted—that is to say, the leg may be commenced at the top and narrowed at the calf and heel, the latter in this case consisting of a web with inner-selvaged edges and being open at the bottom, 55 but presenting at this point looped edges, which may be subsequently connected without forming an objectionable seam. In this case, also, the whole stocking may be formed on the same machine, a tubular web being 60 produced on the two rows of needles until it is desired to form the heel, when one set may be thrown out of action, but permitted to retain their stitches, the heel-web being formed on the other set and being narrowed at the 65 center as it approaches completion, the web

when completed being cast off, so as to permit of the formation of the foot-tube upon both sets of needles.

Although we have described a special form of machine for the production of the stocking, we are not necessarily limited to the use of such a machine, as it will be evident that the tubes for the leg and foot of the stocking can be produced in the manner set forth in our application filed March 26, 1889, Serial 75 No. 304,865, if desired.

Having thus described our invention, we claim and desire to secure by Letters Patent—

1. A stocking having a seamless tubular leg 80 and a heel-pocket with selvaged front edges and shaped seamless lower corner, due to the varying length of the courses of stitches at and near the bottom of the heel, and having the body of the foot composed of a seamless 85 tube, the upper portion of which at the instep forms a seamless union with the front of the ankle portion of the leg, the lower portion of the tube being united to the selvaged front edges of the heel-pocket, all substantially as specified.

2. A stocking having a heel-pocket with selvaged front edges and shaped lower corner, due to the varying length of the courses at and near the bottom of the heel, and having a seamless tubular leg with shaped calf, 95 due to the varying length of the courses in the calf portion of the tube, the body of the foot being composed of a seamless tube, the upper portion of which at the instep forms a 100 seamless union with the front of the ankle portion of the leg, the lower portion of the tube being united to the selvaged front edges of the heel-pocket, all substantially as specified.

3. A stocking having a seamless tubular leg and a seamless heel-pocket with selvaged front edges, the body of the foot consisting of a seamless tube, the upper portion of which at the instep forms a seamless union with the front of the ankle portion of the leg, the lower portion of the tube being united to the selvaged front edges of the heel-pocket, all substantially as specified.

4. A stocking having a seamless tubular 115 leg and a heel-pocket with selvaged front edges, the body of the foot consisting of a seamless tube, the upper portion of which at the instep forms a seamless union with the front of the ankle, the lower portion being 120 united to the selvaged front edges of the heel-pocket, and the tube having a series of wales dropped therefrom at and near the toe, and having its front edges looped together across the toe, all substantially as specified.

5. A stocking having a seamless tubular leg and a heel-pocket with selvaged front edges, the body of the foot consisting of a seamless tube, shaped by having a series of wales dropped therefrom at toe and instep,

the top of the tube at the instep forming a
seamless union with the front of the ankle,
the lower portion of the tube being united to
the selvaged front edges of the heel-pocket,
5 and the front edges of the tube being looped to-
gether across the toe, all substantially as
specified.

In testimony whereof we have signed our

names to this specification in the presence of
two subscribing witnesses.
